METHOD OF FORMING CAM LEVERS

Clarence E. Budd, South Bend, Ind., assignor to
Bendix Aviation Corporation, South Bend, Ind.,
a corporation of Delaware

Application September 28, 1933, Serial No. 691,361

1 Claim. (Cl. 29—152.1)

This invention relates to vehicle brakes and elements thereof, and most particularly to processes for forming a cam lever which is one of the brake elements.

5 An object is to cheapen the cost of the cam lever.

Further objects and features of the invention will be apparent after a reading of the subjoined specification and claim, and after a consideration 10 of the accompanying drawings in which:

Figure 1 is a view in section of a brake illustrating my invention;

Figure 2 is a view in perspective of a cam lever forming a part of the brake assembly;

15 Figure 3 is a view in section of a rolled plate used in the process of forming the lever shown in Figure 2;

Figure 4 is a view in plan of a plate such as that of Figure 3, showing a lever sheared from the 20 plate and showing in dotted lines how other levers may be sheared or stamped therefrom.

Figure 5 is a sectional view along the line 5—5 of Figure 1, showing the anchor bracket;

25 Figure 6 is a view in side elevation of a stamping forming a portion of the anchor bracket; and

Figure 7 is a view in side elevation showing a forging forming another portion of the anchor bracket.

30 Referring in detail to the drawings, it may be seen that I have illustrated a brake including a drum 10, a backing plate 12, and a pair of brake shoes 14 and 16.

The shoes are adapted to be spread into contact 35 with the drum 10 by means of a cam lever 18, which is formed with a pair of lugs 20 and 22 interposed between the ends of the shoes and with a cut out portion 23 surrounding a pin 24 against which the ends of the shoes rest in the

40 "off" position of the brake. The lever 18 is formed at the end thereof opposite to the lugs 20 and 22 with a hook 26 connected to a tension element 28 by means of which the brake is operated. The levers are formed with ridges 54 and

45 56 which serve to support and position the lever between the rib of the shoe 14 and the backing plate 12. A lateral offset is provided near the hook end of the lever to provide clearance between the lever and the shoe rib so that the clevis on the end of the tension member 28 may engage 50 the lever and operate freely.

The opposite ends of the shoes 14 and 16 are 55 pivotally connected to pointed strut links 30 and 32 respectively. The links are guided by a housing formed by a stamping 34 and a forging 36, and at their pointed ends bear upon a wedge 38. The forging 36 is formed with a pair of grooved

5 lugs 35 and 37, the grooves coacting with the roof of the stamping 34 to form a pair of cylindrical guideways for the strut links 30 and 32. The wedge may be screwed in or out of a bore 40 formed in a boss 41 on the forging 36, in order to adjust the position of the shoes. The forging 36 is riveted to the backing plate 12 and the stamping is secured to the forging as by welds 42. Thus it may be seen that in the braking operation, the shoe which does most of the braking anchors 10 through its strut link on the wedge 38 and thence through the forging 36 on the backing plate 12.

The construction described above is claimed in my divisional application No. 62,399, filed February 5, 1936. 15

Springs 44 and 46 are provided for returning the shoes to the normal released position when tension on the element 28 is relieved.

It is believed that the operation of my improved 20 brake will be obvious from the above description. When the operator desires to apply the brakes, he pulls on the tension element 28, thus rocking the lever 18 and spreading the shoes 14 and 16. The lever 18 may float with the movement of the shoes 14 and 16. The shoes anchor as described above 25

through the adjustable wedge 38. When necessary to adjust the shoes on account of lining wear or otherwise, the wedge 38 may be screwed in to spread the anchor ends of the shoes. 30

I prefer to form the cams 18 in the following manner: I roll a sheet of metal 52 to the form shown in Figure 3, thus forming the ridges 54, 56, and 58. Thereafter I shear the levers one after the other from the rolled sheet of metal. Thus the lever 18 may be sheared as from 60 and additional levers may be sheared as at 62 and 64. Simultaneously with the shearing of each lever 18, I shear the cut out portion 23. 35

It is to be understood that the above described 40 embodiments of my invention are for the purpose of illustration only, and various changes may be made therein without departing from the scope of the invention.

I claim:

The process of forming cam levers, which 45 comprises rolling a sheet of metal to a desired section with a relatively large ridge at one end, a pair of smaller ridges on opposite sides and out of alignment adjacent the center thereof, and a slightly offset portion adjacent to the opposite end and thereafter shearing a series of levers therefrom, and simultaneously with the shearing of each lever, shearing a cut out portion from the central part of the ridged end of the lever and forming a hook on the other end. 50

CLARENCE E. BUDD. 55
